[57] ABSTRACT

A workpiece treating apparatus includes a slatted barrel for holding the workpieces during rotation of the barrel. A draw bar is disposed generally parallel to the barrel slats and has workpiece engaging pawls thereon. The draw bar is mounted for oscillatory movement and for rotational movement about its own axis so that the pawls can engage the workpieces and pull them forward in the barrel and can then be disengaged from the workpieces whereby the pawls may return to their original position.

WORKPIECE TREATING APPARATUS

This is a continuation, of copending application Ser. No. 65,465, filed Aug. 20, 1970 now abandoned.

BACKGROUND OF INVENTION

The device of copending application Ser. No. 553,183, filed May 26, 1966, represents a significant advancement in the high volume cleaning of castings, such as automobile cylinder heads, engine blocks, and the like. This axi-flow device utilizes blast cleaning to remove cast sand and scale from the castings. High volume production is accomplished through the use of a rotatable barrel which is made in skeletal form by a plurality of longitudinal slats which are so arranged as to hold the castings during rotation of the barrel so that the castings and barrel rotate together. In this manner, all of the surfaces of the castings are exposed to the blast cleaning operation.

Due to the many depressions and deep openings in such parts as castings, thorough cleaning becomes a problem. When castings are conveyed thru the blast area by confining them between long wearing alloy bars and rotating the castings under the blast stream, as with conventional axi-flo machines, usually the ends of the castings are, to some degree, shielded by adjacent castings. Many methods have been devised for separating the workpieces while they are being blast cleaned, thus exposing the ends to the full application of the blast streams. Some of these systems are too intricate to withstand constant exposure to shot or grit blasting without frequent breakdowns or jamming. Other systems are in the way of the blast streams and blind certain areas of the castings against effective cleaning.

Various attempts to separate the workpiece are disclosed in the U.S. Pat. No. 3,626,641, issued Dec. 14, 1970 and in U.S. Pat. No. 3,534,504, issued Oct. 20, 1970. Additionally U.S. Pat. Nos. 2,918,071 and 3,517,465 are of interest to the general field of this invention.

SUMMARY OF THE INVENTION

An object of this invention is to provide a workpiece treating apparatus which overcomes the above disadvantages.

In accordance with this invention the workpiece treating apparatus comprises a slatted barrel for holding the workpieces during rotation of the barrel. A draw bar is disposed generally parallel to the barrel slats and has workpiece engaging pawls thereon. The draw bar is mounted for oscillatory movement and for rotational movement about its own axis so that the pawls can engage the workpiece and pull them forward in the barrel and can then be disengaged from the workpieces whereby the pawls may return to their original position.

Advantageously, the draw bar is mounted for rotation with the barrel and is interlocked with the barrel rotation drive for synchronization of the rotational and oscillatory movements. The oscillatory means may include dwell periods at the end of each forward and return stroke so that the pawl may move into and out of engagement with the workpieces during these dwell periods.

In an advantageous form of this invention, a stationary cam may be mounted on a central shaft which is coaxial with the axis of rotation of the barrel. A follower is connected to the draw bar and rides on the cam track

of the cam during rotation of the barrel to effectuate the rotational movement of the draw bar about its own axis.

Another feature particularly noteworthy is the inclusion of a safety mechanism to prevent damage should the pawls fail to properly engage the workpiece by, for example, striking a workpiece rather than moving in back of it. The safety mechanism may include an arm rigidly connected to the draw bar with a spring housing or chamber arranged on the follower. Resilient means or a spring is disposed in the chamber and reacts against the arm to transmit the rotational movement of the follower to the draw bar during normal operation. If, however, the pawls should strike the workpiece during abnormal operation, the follower would continue to rotate but the spring would not cause the draw bar to rotate since the spring would be compressed by the non-rotating arm.

THE DRAWINGS

FIG. 1 is a side elevation view partly in section of an apparatus in accordance with this invention in one stage of operation;

FIG. 2 is a side view similar to FIG. 1 in a different phase of operation;

FIG. 3 is a plan view of the apparatus shown in FIG. 1;

FIG. 4 is an elevation view of a portion of the apparatus shown in FIGS. 1-3;

FIG. 5 is a schematic elevation view of the cam mechanism utilized in the apparatus shown in FIGS. 1-4;

FIG. 6 is a cross-sectional view taken through FIG. 4 along the line 6-6;

FIGS. 7-9 are end elevation views similar to FIG. 6, but in different phases of operation;

FIGS. 10-11 are end elevation views of the safety mechanism utilized in this invention in different phases of operation;

FIG. 12 is a plan view partly in section of the safety mechanism shown in FIG. 10; and

FIG. 13 is an elevation view of an end pawl utilized with this invention.

DETAILED DESCRIPTION

FIGS. 1-2 show an apparatus 10 which includes a housing 12 having an axial flow barrel 14 therein. Barrel 14 is of the same general construction as the barrel shown and described in copending application Ser. Nos. 553,183, filed May 26, 1966; U.S. Pat. No. 3,534,504, dated Oct. 20, 1970; and U.S. Pat. No. 3,626,641, dated Dec. 14, 1971, the details of which are incorporated herein by reference thereto. In general the apparatus includes an endless conveyor 16 which transports workpieces such as castings 18 to the open end of barrel 14. Any suitable feed device may be used. For example a cradle-walking beam arrangement 20 may dispose a casting at the barrel entrance and a pawl 36 may pull the castings one at a time into the barrel. Barrel 14 is of skeletal form and includes support drum sections 22, 23 which are spanned by elongated slats 24. The particular arrangement of slats 24 is such that the slats generally conform to the shape of the workpieces 18 so as to hold the workpieces during rotation of the barrel whereby the barrel and workpieces rotate together. Any suitable drive means 26 may be utilized for rotating the barrel. Barrel 14 continuously

rotates in one direction. The parts are moved through the barrel, as later described, and during the rotation are exposed to the blast streams projected by conventional centrifugal throwing wheels 28. After the workpieces are cleaned they are deposited upon endless conveyor 30 at the discharge end of the barrel.

The present invention is particularly concerned with the means for spacing and conveying the workpieces through the barrel so as to expose the ends of the workpiece, as well as the other surfaces, to the blast stream to maximize the cleaning action. In general, this arrangement includes a draw bar 32 disposed generally parallel to slats 24. The draw bar rotates with the barrel and is supported for longitudinal movement in any suitable manner, by for example, sliding in faces 27 of drum sections 22, 23. The draw bar is capable of longitudinally oscillating in forward and return strokes by means of oscillating mechanism 34. A plurality of pawls 36 are mounted on the draw bar 32 in such a manner that during a dwell period at the end of a return stroke of the draw bar, the draw bar and its pawls rotate about the draw bar axis so that each pawl engages a workpiece. The draw bar and engaged pawls then rotate with the barrel during the cleaning action to maintain the workpiece spacing. The draw bar is then moved in a forward stroke by a distance equal to the length of one workpiece plus the space between adjacent workpieces so that the workpieces are indexed through the barrel with the end workpiece being discharged while a new workpiece is pulled into the barrel.

Oscillating mechanism 34 is of any suitable construction and may, for example, be a unit which is commercially available. Since the specific details of the oscillating mechanism do not form a part of this invention, it will be described only where necessary for an understanding of the invention. The oscillating drive is interlocked with barrel drive shaft 38 so as to synchronize the rotational movement of the barrel with the oscillatory movement of draw bar 32. Accordingly, the rate of cleaning can be varied without regard to other adjustments.

The oscillating mechanism 34 imparts a gradually accelerated axial movement and a gradually decelerated movement at the end of each stroke, while dwell periods are provided between the strokes. Additionally, the axial movement includes a rapid return stroke.

As shown in FIGS. 1-3 oscillating mechanism 34 includes a bifurcated support arm 40 having a yoke end 42. A pair of bars 44 are connected to the yoke at one end and at their other end are connected to sleeve member 46. Sleeve 46 has an offset arm 48 and terminates in a further sleeve member 50, which in turn is rigidly but rotatably connected to draw bar 32. A central shaft 52 is mounted on the outer end of barrel 14 co-axial with the axis of rotation of the barrel. Shaft 52, however, does not rotate or move longitudinally and is also suspended from any suitable support 54. Shaft 52 has the dual function of providing a means upon which a stationary cam 56 may be mounted (as later described) and of providing guide means for longitudinally movable sleeve member 46.

FIG. 5 shows an elevation view of the stationary cam 56 which is connected to central shaft 52 by means of key 58. Cam track 60 is disposed about the periphery of cam 56. One end (in the form of a roller) 62 of a follower 64 rides in the cam track 60 while the opposite end is secured to draw bar 32. Since cam 56 is station-

ary, the rotational movement of draw bar 32 caused by its connection to barrel 14 causes follower 64 to also rotate. During the movement of follower 64 the follower roller 62 rides in cam track 60 which in turn causes draw bar 32 to rotate about its own axis at predetermined cam track positions. As shown in FIG. 5 the cam track 60 includes a pair of dwell arcs A and B which in the illustrated embodiment are 80° and 120°, respectively. Between the arcs A and B are active arcs C and D. When follower roller is in the arc A there is a dwell in that draw bar 32 does not rotate about its own axis and the pawls remain disengaged from the workpiece. As the follower 62 continues to move and is in arc C, draw bar 32 is caused to rotate so that the pawls move toward engagement in back of the workpiece. This rotation continues until arc B is reached. Arc B represents another dwell period when there is no rotation of draw bar 32, whereupon the pawls remain engaged with the workpieces. When the follower roller 62 is in arc D, draw bar 32 again rotates to disengage the pawls from the workpieces. FIG. 5 also illustrates the positions assumed by the draw bar and the follower at the end of the forward stroke of the draw bar as designated by the arrow E and at the end of the draw bar return stroke as designated by the arrow F.

FIGS. 6-9 show the draw bar and pawl arrangement during different phases of operation. As illustrated in FIG. 6, the pawl 36 is moving into engagement behind the workpiece 18. This movement takes place during the dwell period of the oscillating drive 34 at the end of the return stroke.

FIG. 7 shows a subsequent stage of operation wherein the pawl 36 is fully engaged with the workpiece 18. When the various parts are in this position, the barrel 14 continues to rotate and the workpieces 18 are subjected to the primary blast treatment. Oscillating drive 34 thereupon pulls draw bar 32 forward while another workpiece is being inserted into the barrel.

FIG. 8 shows the positions of the various parts when the last workpiece 18 is about to be discharged from the barrel. FIG. 9 illustrates the position of the parts when the workpiece is being discharged and the pawl 36 is moving out of engagement by the rotation of draw bar 32. This cycle is continuously repeated with the rotation taking place in the same direction.

As also shown in FIG. 9, the falling workpieces 18 are received on a discharge conveyor 30. FIGS. 1 and 4 most clearly show the provisions made to permit the cleaned workpiece to be discharged by simply falling from the barrel onto conveyor 30. As illustrated therein, the discharge drum section 23 includes an opening 25. In this drum section 23 are a set of slats 24a which are shorter than the remaining slats 24b or terminate upstream from slats 24b thereby creating an opening in registry with opening 25 at the discharge end of the barrel.

The pawls 36 may have any suitable construction. Generally, however, each pawl includes a sleeve 66 which fits around draw bar 32 and is rigidly secured thereto by key 68. (See FIGS. 1, 2, and 6.) A shank 70 extends from sleeve 66 and terminates in a hooklike contact surface 72. In this manner, there is a minimum blinding of the workpieces resulting from the pawls.

In general a single pawl is disposed in back of every workpiece to assure a proper indexing of the workpieces. When the draw bar is reciprocated, however, clearance difficulties arise adjacent the slat supporting

faces 27 in the drums 22,23 and special provisions must be made. In this respect a separate pawl could not be provided adjacent these faces 27 since the reciprocating draw bar would cause the pawls to strike the faces 27. FIG. 13 shows the construction of pawls 36a which are designed to overcome these difficulties. As illustrated therein, the workpiece engaging surface 72 includes an offset extension 74 which also terminates in a workpiece engaging surface 76. Workpiece engaging surface 76 is so arranged as to fit into an opening in a workpiece 18a while engaging surface 72 pushes against the preceding adjacent workpiece 18b. Accordingly, the same pawl 36a simultaneously pushes workpiece 18b and pulls succeeding workpiece 18a. Such pawls 36a may be provided wherever there are clearance difficulties.

The pawls 36 (or 36a) are particularly advantageous since these are heavy durable pawls which are able to withstand the conditions inside a blast area. The pawls which communicate with the workpiece have a small contact area and stand away from the workpiece so as to avoid blinding of certain areas of the workpiece during blast cleaning. It is also noteworthy that the main parts of the mechanism for pulling the workpieces are located outside of the blast area, thus providing for protection, access and proper lubrication. Moreover, the spacing between the workpieces which facilitates the end blast cleaning is maintained throughout the movement of the workpieces in the blast area.

FIGS. 10-12 show another aspect of the invention relating to the safe guard or safety mechanism 78. Inclusion of this mechanism is an important feature. If, for any reason, one or more of the castings being treated should be out of position, under such circumstances the engaging pawl or pawls would strike the workpiece or workpieces. The safety mechanism prevents jamming, damage or breakage which would otherwise occur. In this respect, the safety mechanism prevents the full force of cam 56 from being transmitted to draw bar 32. In the illustrated embodiment, follower 64 includes a chamber 80 which houses a spring 82. Safety arm 84 is located at the end of chamber 80 and is rigidly connected to draw bar 32. Spring 82 reacts against arm 84 so that under normal conditions the movement of the follower is transmitted by spring 82 to safety arm 84. Thus as follower 64 rotates arm 84 is also caused to rotate. Since arm 84 is rigidly connected to draw bar 32, the rotational movement is transmitted to the draw bar whereupon pawls 36 also rotate. FIG. 10 shows the position assumed by the various elements during normal operation. As also illustrated therein, a tensioning screw 86 is provided to adjust the tension of spring 82.

FIG. 11 shows the relative positions of the various elements during abnormal operating conditions. As indicated therein, pawl 36 has contacted the workpiece 18 rather than sliding behind it. Since the barrel 14 continues to rotate, however, follower 64 also continues to rotate. As follower 64 rotates spring 82 is compressed by arm 84 because the arm, its draw bar, and the pawl can no longer rotate. Thus follower 64 is permitted to continue rotating without causing jamming or breakage by otherwise transmitting the full force of the rotation to the draw bar 32. If desired, the entire apparatus 10 may be automatically stopped by, for example, the actuation of suitable switching (not shown) to either set off an alarm or to automatically deactivate the various

drives. In this respect an arm 90 may be disposed at the end of mechanism 78 parallel to its end surface. During abnormal operation the arm 90 would become tilted and would contact a stationary switch 92 to initiate the desired control operation.

What is claimed is:

1. A workpiece treating apparatus comprising a barrel made of skeletal form, said barrel being formed from a plurality of spaced longitudinal slats for holding a plurality of workpieces during rotation of said barrel, means for rotating said barrel about an axis of rotation, a draw bar disposed generally parallel to said slats, said draw bar being mounted for longitudinal movement backward and forward generally parallel to the axis of rotation, workpiece engaging means fixed on said draw bar, means for radially moving said workpiece engaging means to a position for engaging said engaging means with the workpieces and to another position for disengaging said engaging means with the workpieces, axially oscillating means for moving said draw bar forward and backward, and means for synchronizing said moving means and said oscillating means for causing said engaging means to be engaged with the workpieces on a forward movement and to cause said engaging means to be disengaged from the workpieces on a backward movement of said draw bar.
2. An apparatus as set forth in claim 1 wherein said draw bar is connected to said barrel for rotation with said barrel.
3. An apparatus as set forth in claim 2 wherein said barrel rotation means and said oscillating means are interlocked for synchronization of the rotational movement of said barrel and oscillatory movements.
4. An apparatus as set forth in claim 2 wherein said oscillating means has a dwell period at the end of each forward and backward movement.
5. An apparatus as set forth in claim 4 wherein said means for moving said workpiece engaging means includes cam means for causing said workpiece engaging means to selectively engage and disengage the workpieces during the dwell periods of said oscillating means.
6. An apparatus as set forth in claim 5 wherein said cam means includes a stationary cam mounted substantially coaxial with the axis of rotation of said barrel, and a follower connected to said draw bar and riding on the cam track of said cam.
7. An apparatus as set forth in claim 6 wherein said cam is mounted on a stationary shaft which is coaxial with the axis of rotation of said barrel, said central shaft further comprising guide means for said oscillating means.
8. An apparatus as set forth in claim 6 including a safety mechanism mounted on said draw bar for preventing said draw bar from rotating about its own axis when said workpiece engaging means is unable to be properly disposed against a workpiece.
9. An apparatus as set forth in claim 8 wherein said safety mechanism includes an arm rigidly connected to said draw bar, a chamber connected to said follower, and resilient means in said chamber reacting against said arm to transmit the rotational movement of said follower to said draw bar during normal operation and to be compressed by said arm during abnormal operation whereby said draw bar does not rotate with said follower during abnormal operation.

10. An apparatus as set forth in claim 9 including inactivating means for inactivating said apparatus upon compression of said resilient means.

11. An apparatus as set forth in claim 4 wherein said workpiece engaging means includes a plurality of pawls, each of said pawls having a shank rigidly connected to said draw bar, and a workpiece engaging surface at the free end of said shank.

12. An apparatus as set forth in claim 11 wherein at least one of said pawls includes an offset portion extending from its workpiece engaging surface, and a further workpiece engaging surface on said offset portion whereby the same pawl can simultaneously push one workpiece and pull an adjacent workpiece.

13. An apparatus as set forth in claim 2 wherein said plurality of slats include a set of slats which terminate upstream from to remaining slats to create an open area through which a workpiece may fall, and a discharge conveyor disposed under said open area.

14. An apparatus as set forth in claim 2 wherein said draw bar is mounted for rotation about its own axis and said means for moving said workpiece engaging means rotates said draw bar to a position for engaging said engaging means with the workpieces and to another position for disengaging said engaging means with the workpieces.
